BELT BUCKLE

Furnie Deaver, P.O. Box 254,
Bladenboro, N.C. 28320

Filed Feb. 18, 1975, Ser. No. 550,510

Term of patent 14 years

Int. Cl. D2—07

U.S. Cl. D2—427

FIG. 1

FIG. 2

FIG. 3

FIG. 4

FIG. 5

FIG. 6

FIG. 1 is a top perspective view of a belt buckle showing my new design;

FIG. 2 is a right side elevational view thereof;

FIG. 3 is a top plan view thereof;

FIG. 4 is a top edge elevational view thereof, the bottom edge being a mirror image thereto;

FIG. 5 is a left side elevational view thereof;

FIG. 6 is a bottom plan view thereof.

I claim:

The ornamental design for a belt buckle, as shown and described.
